UNITED STATES PATENT OFFICE.

ROBERT LOUDON WALKER, OF BOSTON, MASSACHUSETTS.

FURNACE.

SPECIFICATION forming part of Letters Patent No. 439,706, dated November 4, 1890.

Application filed March 8, 1890. Serial No. 343,143. (No model.)

To all whom it may concern:

Be it known that I, ROBERT LOUDON WALKER, of Boston, in the county of Suffolk, and State of Massachusetts, have invented 5 a new and useful Improvement in Furnaces, of which the following is a specification, reference being had to the accompanying drawings, in which—

Figure 1 is a longitudinal section of a part 10 of one form of boiler embodying my invention, and Fig. 2 is a section at line 3 3 of Fig. 1.

My invention is an improvement on the furnace described in my pending application, Serial No. 339,005, filed February 3, 1890; and 15 it consists in the combination of a deflector with a grate, one portion of which is shaken independently of the other portion.

In the drawings, A A' is the grate, B the fire-box, B' the deflector, and D the ash-pit. 20 Deflector B' is so arranged in the fire-box that it directs the products of combustion arising from the duller or greener part of the fire on one section of the grate over a brighter part of the fire on an independent section of 25 the grate.

I have discovered that by keeping a part 30 of the fire much brighter than the rest of the fire the products of combustion which pass over this quickened portion of the fire are consumed, smoke prevented, and fuel saved. I accordingly form the grate in sections A A', and make one section A', over which products of combustion pass to the flues, so that 35 it can be rocked or shaken independently of the rest of the grate. Section A' is shown as a rocking grate of ordinary construction, capable of being rocked by a rod a in the usual way. The rest of the grate may be either a 40 rocking grate, as the part A in Fig. 1, or a stationary grate, as shown at A in Fig. 2. By agitating section A' with sufficient frequency 45 to keep the coal on it much looser and freer than the coal on the other part A of the grate, a much stronger draft is produced through section A' than through section A, and when the products of combustion are deflected upon and over this quickened fire by the deflector they are very perfectly consumed.

50 I am aware of McDowell's patent, No. 406,757, dated July 9, 1889, Nepilly's patent, No. 261,474, dated July 18, 1882, and Ritter's patent, No. 290,270, dated December 18, 1883, and disclaim all that is shown in them, fur-

naces embodying my invention differing materially from the furnace shown in McDowell's patent in having a shaking grate under that part of the fire upon which the products of combustion arising from the green part of the fire are deflected. In McDowell's furnace 55 there is no provision for nor any suggestion of quickening one part of the fire, and the deflector does not direct products of combustion upon a shaking grate, but upon a trap-door, which is lowered to remove clinkers, 60 but is not and cannot be practically shaken. In Nepilly's contrivance the products of combustion arising from the brighter portion of the fire are deflected over the green fire. This is obviously a radically different plan and construction from mine. 70

In Ritter's furnace there is no deflector, and there is no suggestion in his patent of directing products of combustion arising from green fire over quickened fire, and, in fact, 75 his fire is of substantially uniform intensity, for his coal is, by a peculiar construction, directed over the whole grate-surface. Ritter's arch is a simple arched roof for the fire-chamber, and this roof has no downward projection to alter the course of the products of combustion. My new furnace also differs radically from both Ritter's and McDowell's in having a shaking grate, where Ritter and McDowell have trap-doors that may, indeed, 80 be shaken, but which are not shaking grates in any practical sense or for any practical purpose. Should it be attempted to effectively shake Ritter's trap-door K, a considerable portion of the unconsumed coal in the 85 fire over it would be lost and much fuel wasted. The same is true to a far greater degree of McDowell's furnace, owing to the inclination of McDowell's trap-door M'. 90

What I claim is—

95 In a furnace, the combination of a deflector B', with a grate made in independent sections A A', the section A' being a shaking grate, and the deflector B' projecting into the fire-box toward the grate to direct products of combustion from the greener fire on section A over the brighter fire on section A', all substantially as and for the purpose described.

ROBERT LOUDON WALKER.
